STOVE

John Bilan, Flint, Mich.

Application June 5, 1944, Serial No. 538,778

1 Claim. (Cl. 126—58)

The present invention relates to stoves, and has for its main object the provision of a stove made of a number of parts which may be readily assembled or disassembled.

A still further object of the present invention is the provision of a stove with increased radial surface so as to obtain therefrom a maximum of heating efficiencies.

With the above general objects in view and others that will appear as the invention is better understood, the same consists in the novel construction, combination and arrangement of parts hereinafter more fully described and illustrated in the accompanying drawing and pointed out in the appended claim.

In the drawing forming a part of this application, and in which like designating characters refer to corresponding parts throughout the several views;

Fig. 1 is a front elevational view, partly in section, of the stove;

Fig. 2 is a cross-sectional view on line 2—2 of Fig. 1;

Fig. 3 is a cross-sectional view on line 3—3 of Fig. 1;

Fig. 4 is a perspective view of one of the baffle elements used in connection with the stove; and

Fig. 5 is an enlarged horizontal cross-sectional view through the corner of a stove.

Referring in detail to the present drawing, the stove includes an ash box 10, including bottom wall 11 and four vertical side walls 12, integrally formed with said bottom wall 11. Provided in the front vertical wall 12 is door 13, the latter provided with a plurality of conventional slots 14 with a slidable plate in the rear thereof for the purpose of regulating the draft. Said door 13 affords access to said ash box 10 for the purpose of removing ashes therefrom.

Ash box 10 is supported upon legs 15, one at each corner of the stove. The upper ends of said legs 15 are slotted for receiving therewithin in a frictional relation angle irons 16, which extend upwardly and above said ash box 10.

The upper ends of vertical walls 12 are grooved for providing a seat for the marginal edge of plate flange 17, from which a pair of upwardly tapering side walls 18, and a pair of straight end walls 19 project. Said walls 18 and 19 are integrally formed with said plate flange 17 for defining a fire box 20. All of said walls 18 and 19 are spaced from the continuation planes of said vertical walls 12 of ash box 10. The bottom of said fire box 20 is open for receiving grate 21 upon which fuel is adapted to burn and through

which ashes are adapted to fall into the ash box 10. The front end wall 19 is provided with door 22 through which access is afforded into said fire box 20.

The upper ends of walls 18 and 19 are grooved for receiving a top wall 23, which completes the structure of said fire box 20.

Said top wall 23 has a plurality of annular openings 24, each of which is adapted to receive collar 25, projecting above said top wall 23.

Cooperating with each of said collars 25 is a funnel-shaped baffle element 26, having at its upper wider end a plurality of arms 27 integrally formed with and laterally projecting therefrom. Said baffle elements 26 are receivable within upper ends of collars 25, with arms 27 resting upon upper ends of said collars 25. The diameter of each of said baffle elements 26 is shorter than the diameter of said collars 25 so that when said baffle elements 26 are in an operative position with relation to said collars 25, the upper ends of said baffle elements 26 with the adjacent inner periphery of said collars 25 define annular slots 28, through which smoke and combustion gases are adapted to pass from said fire box 20 and above collars 25. The function of said baffle elements 26 is to retard the escape of smoke and combustion gases from fire box 20 so that the same may be more thoroughly consumed while still therewithin.

The stove further includes a plurality of flues 29, the lower ends of which are annular and the upper ends of which are flattened to define an elliptical formation on horizontal cross-section. The lower ends of said flues 29 are positioned over said collars 25 and frictionally engage the latter over their outer peripheries as is clearly seen in Fig. 1.

Positioned over said flues 29 and supported thereby is dome 30 which has a straight bottom wall 31 and a pair of end walls 32 and an arcuate roof wall 33. Made in said bottom wall 31 is a plurality of oblong or elliptical openings 34, from the margins of which sleeves 35 of like formation downwardly project, said sleeves 35 being integrally formed with said bottom wall 31. Engaging the outer peripheries of said sleeves 35 are the upper elliptical ends of said flues 29.

Seated upon the ends of vertical walls 12 and on the same plane therewith are four walls 36 of hood 37 enclosing fire box 20, flues 29 and dome 30. Top wall 38, positioned upon the upper ends of walls 36, completes the structure of said hood 37.

Said walls 36 are maintained in an operative

position by means of said angle irons 16, as is clearly seen in Figs. 3 and 5, and to maintain said angle irons 16 a plurality of corner brackets 39 are attached to vertical walls 12 as well as to walls 36.

It is observed that fire box 20, flues 29 and dome 30 are all spaced from side walls 36 and top wall 38 of hood 37. To provide access to door 22 of fire box 20 a rectangular jamb 40 is provided, the rear end of which connects with the front wall 19 of fire box 20, and the front end of which connects with the adjacent front wall 36 of hood 37. Said front wall 36 is correspondingly cut away for providing access to said door 22 through jamb 40.

Each of end walls 32 of dome 30 is provided with a horizontally extending pipe 41, each extending through the front or rear wall 36 to selectively carry away smoke and combustion gases from dome 30 into the chimney flue. One of said pipes 41 not in use may be closed by cap 42.

Made adjacent the lower ends of side walls 36 of hood 37 is a plurality of openings 43, through which air is adapted to pass into said hood 37 to be heated by the radiating fire box 20, flues 29 and dome 30 and to flow in an upward direction to ultimately escape into the dwelling through a plurality of openings 44 made in top wall 38 of hood 37. The inclined side walls 18 of fire box 20 retard the flow of air through said openings 43 upwardly in order to facilitate a thorough absorption of heat by the air when it comes in contact with said side walls 18 and before the same escapes upwardly through spaces defined by the upper ends of said side walls 18 and the adjacent side walls 36 of hood 37.

From the hereinabove description it will be apparent that the stove herein disclosed is made of plurality of parts which are capable of quick assembly and disassembly, and that the same

has a large area exposed of the parts through which flame and combustion gases come in contact, whereby the greatest degree of radiation is brought about for the purpose of enhancing the efficiency of the stove.

It is further observed that a number of flues 29 may be varied, either decreased or increased, depending upon the size of the stove and its capacity. Some of said flues 29 may be entirely eliminated and a lesser number thereof used, sufficient however to support dome 30. Collars 25 and sleeves 35 in those flues 29 which are eliminated, may be capped preventing escape of combustion gases through those in connection with which flues 29 are not in use.

While there is described herein a preferred embodiment of the present invention, it is nevertheless to be understood that minor changes may be made therein without departing from the spirit and scope of the invention as claimed.

What I claim as new is:

In a stove comprising a fire box including a top wall thereof, a plurality of openings made in said top wall, a collar seated within each of said openings, flues each connecting by its lower end with one of said collars, a dome overlying the upper ends of said flues and supported thereby, said dome having a plurality of openings, and a sleeve extending and downwardly depending from the marginal edge of each of said openings, said sleeves being receivable by the upper ends of said flues: that improvement comprising inverted conical baffle members positioned within said collars, said baffle members having lateral extensions engaging the upper ends of said collars, the combustion gases being adapted to pass from said fire box into said flues through said collars and past said baffle members and into said dome through said sleeves.

JOHN BILAN.
